UNITED STATES PATENT OFFICE.

THEODORE H. SORLIEN AND OLE A. KNUDTSON, OF MINNEAPOLIS, MINNESOTA.

FRICITION COUNTERPOISED WINDLASS-DRUM.

1,301,186.

Specification of Letters Patent.

Patented Apr. 22, 1919.

Application filed May 7, 1917. Serial No. 166,814.

To all whom it may concern:

Be it known that we, THEODORE H. SORLIEN and OLE A. KNUDTSON, citizens of the United States, residing at Minneapolis, in the county 5 of Hennepin and State of Minnesota, have invented certain new and useful Improvements in Friction Counterpoised Windlass-Drums; and we do hereby declare the following to be a full, clear, and exact description of the invention, such as will enable others skilled in the art to which it appertains to make and use the same.

Our invention has for its object to provide a friction counter-poised windlass drum intended for general use, but especially adapted for use in connection with ceiling beds of the type disclosed in United States Letters Patent No. 1,065,740, of June 24, 1913 and issued to Theodore H. Sorlien, one of 20 the inventors of the present application.

To the above end, generally stated, the invention consists of the novel devices and combinations of devices hereinafter described and defined in the claims.

25 In the accompanying drawings, which illustrate the invention, like characters indicate like parts throughout the several views.

Referring to the drawings:

30 Figure 1 is a vertical section taken through a portion of a room and a ceiling bed arranged to be raised and lowered by means of the friction counter-poised windlass drum, some parts being shown in different positions by means of broken lines, and some 35 parts being diagrammatically illustrated by the same means;

Fig. 2 is a side elevation of the windlass drum, some parts being broken away and some of the exposed parts being shown in 40 section; and

Fig. 3 is a horizontal section taken on the line 3-3 of Fig. 2.

For the purpose of showing the invention in working position, there is illustrated in 45 the drawings a portion of a room having in its ceiling an opening arranged to receive and hold, when not in use, a ceiling bed which is raised and lowered by means of the friction counter-poised windlass drum.

50 Of the parts of the room shown, the numerals 4, 5, and 6 indicate, respectively, the floor, uprights in one of the partitions, and

ceiling having an opening 7 to receive the bed 8. Extending into the opening 7 is a rectangular supporting flange 9 formed by 55 securing a molding to the ceiling 6. When the bed 8 is lowered, the opening 7 is closed by a panel 10 displaceably supported in said opening on the flange 9. In raising the bed 8, the panel 10 is lifted thereby, as indicated by broken lines in Fig. 1, and the opening closed after the bed 8 enters therein, by a panel 11 carried by and below said bed.

Referring now in detail to the invention, 65 the numeral 12 indicates a horizontally disposed rectangular frame of such length and width as to snugly fit between two of the uprights 5 and not interfere with the walls of the partition. The ends of the frame 12 70 extend both above and below the sides thereof to give additional bearing surfaces and are rigidly secured by lag screws 13 to the respective uprights 5.

Within the frame 12 is a vertically dis- 75 posed windlass drum 14 keyed to a short shaft 15 journaled in bearings 16 formed in the sides of said frame. The rim 17 of the windlass drum has integrally formed with its inner edge portion, an external gear 18. 80 Formed in the periphery of the rim 17 is a spiral groove 19 the convolutions of which extend from the gear 18 to the outer edge portion of said rim. The rim 17 and the hub 20 of the windlass drum are, as shown, integral with a connecting web 21 which has formed therein a plurality of circumferentially spaced annular openings 22 for the sake of lightness. It will be noted that the hub 20 extends entirely inward from the web 90 21 and on the outer face of said web, is an axially located annular flange affording a large hub 23, the purpose of which will presently appear.

Meshing with the gear 18 is a pinion 24 95 keyed to a shaft 25 journaled in bearings 26 formed by extending the sides of the frame 12 downward onto the left hand end of said frame. The outer end of the shaft 25 is extended through the frame 12, and formed 100 angular to receive a crank, not shown, by which the pinion 24, and hence the windlass drum 14 may be rotated. In actual practice, the wall will be provided with a door-

2
equipped opening to afford access to the windlass drum.

Four laterally spaced cables, preferably wire, are laid in the groove 19, as best shown in Fig. 3, and their immediate ends are secured to the windlass drum 14 by inserting the same through holes 28 formed in the rim 17, and then enlarged in any suitable way, so that they cannot pull therethrough. From the windlass drum 14, the cables 27 extend vertically upward between the respective uprights 5, over guide sheaves 29, and thence, horizontally over guide sheaves 30 located one over each corner of the bed 8. The cables 27 from the guide sheaves 30, extend vertically downward through apertures in the panel 10, and are secured one to each corner of the bed 8. The guide sheaves 29 and 30 are secured to the ceiling structure 6 above the opening 7.

From the above description, it is evident that under the rotation of the windlass drum 14, the cables 27 will be wound thereon or unwound therefrom, depending on which way said windlass drum is rotated. When the bed 8 is lowered, the same is supported directly on the floor 4 by folding legs with which said bed is provided. These legs, when the bed is raised, are folded in positions above the panel 11.

The bed 8 and the load carried thereby are sustained by a friction device in different elevated positions while said bed is being either raised or lowered, or while the same is stored in the opening 7. This friction device comprises inner and outer friction disks 31 and 32 respectively, and facings 33 interposed between said two disks, and between the inner disk 31 and the head 14 of the windlass drum. The friction disk 31 is journaled on the hub 23 and has formed on its outer face an axially located annular ratchet 34 in the form of circumferentially spaced segmental notches. Coöperating with the ratchet 34 is a pawl 35 in the form of a ball mounted in a pocket 36 formed in a block 37 detachably secured by screws 38 to the inner face of the outer side member of the frame 12. This pocket 36 is provided with an inclined surface 39 which directs the pawl 35 into interlocking engagement with the ratchet 34. The pawl 35 and ratchet 34 are arranged to lock the friction disk 31 against rotation when the bed 8 is lowered, and to release the same when the bed is raised to permit said friction disk 31 to rotate with the windlass drum 14.

The friction disk 32 is mounted directly on the shaft 15 outward of the hub 23 with freedom for axial movement thereon, but is held for rotation with the windlass drum 14 by a plurality, as shown three, circumferentially spaced bolts 40, which extend through alined apertures in the friction disk 32 and the web 21. The heads of the bolts

40 are countersunk in the outer face of the friction disk 32, and their ends have screw-threaded engagement with a spider bracket 41 through which the hub 20 projects. Coiled springs 42 encircling the bolts 40 are compressed between the web 21 and bracket 41 and yieldingly hold the friction disk 32 under strain to move axially on the shaft 15 toward the friction disk 31.

The facings 33 may be made from fiber 75 or other suitable material and, as shown, there are three members in each set, and which members are circumferentially spaced in respect to each other. One set of the facings 33 are rigidly secured by rivets to the 80 outer face of the web 21 and bears against the inner face of the friction disk 31, and the other set thereof are rigidly secured by rivets to the outer face of the friction disk 31 and bears against the inner face of the 85 friction disk 32. It is important to note that the friction disk 31 is considerably larger in diameter than the friction disk 32, and that the facings 33 are located for action upon the friction disks 31 and 32, just 90 inward of their peripheries. By making the friction disks 31 and 32 of different diameters, and locating the facings close to the peripheries thereof, brings said facings 95 into position for action on concentric surfaces of the friction device, and thereby tends to warp the members thereof and increase the efficiency of the friction device. The frictional contact of the facings 33 with the disks 31 and 32 will cause the friction 100 disk 31 to rotate with the windlass drum 14, while the bed 8 is being raised. The tension of the springs 42 acting on the friction disks 31 and 32 is more than sufficient to sustain the load on the cables 27 and makes it positively necessary to turn the windlass drum 105 14 by the crank, herebefore referred to, to unwind the cables 27 from the windlass drum 14, and lower the bed 8. By adjusting the bolts 40, the tension of the springs 42 110 may be varied, at will.

What we claim is:—

1. The combination with a load to be raised, of a drum, means supporting the load from the drum, a revoluble friction plate, 115 means for limiting the rotation of the friction plate to one direction, a friction coupling set under constantly applied frictional engagement with the drum and friction plate, said coupling also being set under such friction that it will not slip under the load but adapted to slip under a certain force in addition to the load and means for positively rotating the drum in either direction.

2. The combination with a load to be 125 raised, of a drum, means supporting the load from the drum, a revoluble friction plate, means for limiting the rotation of the friction plate to one direction, an adjustable friction coupling set under constantly applied 130

frictional engagement with the drum and frictional plate, said coupling also being set under such friction that it will not slip under the load but adapted to slip under a certain 5 force in addition to the load and means for positively rotating the drum in either direction.

In testimony whereof we affix our signatures in presence of two witnesses.

THEODORE H. SORLIEN.
OLE A. KNUDTSON.
